[57] CLAIM

The ornamental design for a reading stand, as shown and described.

DESCRIPTION

FIG. 1 is a perspective view of a reading stand showing my new design;

FIG. 2 is a right side elevational view, the left side being a mirror image thereof;

FIG. 3 is a rear elevational view thereof;

FIG. 4 is a perspective view of a second embodiment of the reading stand shown in FIG. 1; the broken line showing of a book is for illustrative purposes only and forms no part of the claimed design; and,

FIG. 5 is a rear elevational view thereof.
